UNITED STATES PATENT OFFICE.

CHARLES G. MAYER, JR., OF DURANGO, COLORADO.

CRUSHING-MILL.

1,110,218.

Specification of Letters Patent.

Patented Sept. 8, 1914.

Application filed February 4, 1911. Serial No. 606,556.

To all whom it may concern:

Be it known that I, CHARLES G. MAYER, Jr., a citizen of the United States, residing at Durango, in the county of La Plata and 5 State of Colorado, have invented new and useful Improvements in Crushing-Mills, of which the following is a specification.

The invention relates to crushers, and more particularly to the class of crushing 10 mills for foods or other material.

The primary object of the invention is the provision of a mill of this character in which material delivered thereto may be disintegrated into fine or coarse particles, 15 as the occasion may require.

Another object of the invention is the provision of a mill in which the crushing rollers thereof are arranged in superposed pairs, one roller of each pair being adjustable toward and away from the other of the pair, whereby the material, when delivered thereto, may be disintegrated or crushed into fine or coarse particles to suit the requirement thereof.

25 A further object of the invention is the provision of a mill in which the hopper deflecting walls thereof may be adjusted to increase or decrease the delivery opening for admitting the material contained within the 30 hopper to the crushing rollers, thus avoiding the breaking of the material before the same has been acted upon by the said crushing rollers, one roller of each pair being adjustable, whereby the pairs of rollers may 35 be independently adjusted for the disintegration of material to the required degree.

A still further object of the invention is the provision of a mill of this character in which mechanism is arranged for the driving 40 of one roller of each pair in unison, whereby the disintegration of material will be carried on successively by the continued operation of the machine.

A still further object of the invention is 45 the provision of a mill of this character which is simple in construction, reliable and efficient in operation, durable, and inexpensive in manufacture.

With these and other objects in view, the 50 invention consists in the construction, combination and arrangement of parts, as will be hereinafter more fully described, illustrated in the accompanying drawings, and pointed out in the claims hereunto ap- 55 pended.

In the drawings: Figure 1 is a side elevation of a mill constructed in accordance with the invention. Fig. 2 is a vertical longitudinal sectional view thereof. Fig. 3 is a vertical transverse sectional view. Fig. 4 is 60 a fragmentary side elevation, showing the face plate removed. Fig. 5 is a sectional view on the line 5—5 of Fig. 1.

Similar reference characters indicate corresponding parts throughout the several 65 views of the drawings.

Referring to the drawings by numerals, the crushing mill comprises a hollow body or casing, including vertical side and end walls 10 and 11, respectively, the side walls 70 being extended to provide supporting legs 12, whereby the mill may rest upon a table or other suitable foundation.

In the upper end of the body of the mill is arranged a hopper, comprising downwardly converging adjustable slides 13, the same being engaged in opposed downwardly converging guide grooves 14 formed in the end walls 11 of the body, the side walls at their top edges being beveled, as at 15, to 80 permit the free movement of the slides 13, so that the latter may be adjusted whereby the space between the lower bottom edges may be increased or decreased, this space being provided to form a delivery opening 85 from the hopper to the crushing rollers, as will be hereinafter more fully described.

Below the hopper and supported by the end walls 11 of the body of the mill are superposed pairs of crushing rollers 16 and 17, the rollers 16 being provided with corrugations longitudinally disposed therein to form crushing ribs 18, while the rollers 17 are provided with roughened surfaces 19, the rollers 16 being adapted to disintegrate 90 material into coarse particles as the same is delivered from the hopper to and between the said rollers, while the rollers 17, when in close relation to each other, are adapted to disintegrate the said material into fine particles. The pairs of rollers are provided 95 with journal ends 20 which have their bearings in the end walls 11 of the body of the mill, the journal ends 20 of one roller of each pair being slidably fitted in horizontally disposed elongated guide slots 21 formed in the end walls 11, whereby the roller may be adjusted toward and away from the other roller of the pair, thus increasing or decreasing the space between the 100

105

110

same and the journal ends 20. These adjustable rollers are engaged in suitable openings formed in adjustable plates 22, the latter being slidably fitted in suitable guide ways 23 formed exteriorly on the end walls 11 of the body of the mill. Inclosing the said adjustable plates 22 are suitable housings 24 including removable face plates 25, the housings being suitably secured to the end walls 11 of the body of the said mill. Connected with the adjustable plates 22 are locking members 26, the same being mounted upon the plates 22 by means of hinges 27 and are provided with a plurality of notches 28, the members 26 being projected through suitable slots 29 formed in the ends of the housings 24, and in any one of the notches in each member 26 is adapted to engage with the slotted wall of the inclosures 24, thereby locking the adjustable plates 22 against accidental movement, thus locking the roller in its adjusted position with respect to the other roller of the pair. Suitably secured to the end of one roller of each pair is a sprocket wheel 30, over which is trained a sprocket chain 31, whereby motion from one roller will be imparted to the other. The sprocket wheel 30 fixed to the roller 16 of the uppermost pair is of considerably increased size with respect to the sprocket wheel 30 on the roller 17, thus the roller 17 will be driven at a higher rate of speed than the roller 16, but both of said rollers will be rotated in unison. Suitably fixed to the other journal 20 on the roller 17 carrying the sprocket wheel 30 is a fly wheel 32, while at the end of the journal carrying said sprocket wheel of this roller is fixed a belt wheel 33, over which is adapted to be trained a belt operated through the medium of suitable motor power for the driving of the mill. However, in lieu of the belt wheel 33, a hand crank may be attached to the journal

of the roller 17 for manually operating the same.

What is claimed is:

1. A mill of the class described, comprising a body having its front wall provided with vertically disposed slots, a pair of rollers journaled in the body, blocks slideable on the ends of the body and adapted to receive the journal ends of one of the pair of said rollers, means for adjusting the said single roller and comprising combined lock and operating arms directly pivoted at one end of said blocks and having their opposite ends projecting through said vertical slots of the front wall of the body whereby to move and regulate the adjustment of said blocks, said arms being provided with a plurality of notches adapted for interchangeable engagement with the lower edge of the vertical slot, and removable plates covering the said blocks and forming a housing therefor as described.

2. A mill of the class described, comprising a body having front, rear and end walls, said front walls having vertically disposed slots, guideways formed on the exterior of the said end walls, a pair of rollers arranged within the body, the journaled ends of one of said rollers being mounted in elongated slots in the said end walls, blocks slideable in said guideways and provided with openings in registry with said elongated slots and adapted to receive the journal ends of the said single roller and means connected with the blocks and movable through said vertical slots of the casing for adjusting said rollers as described.

In testimony whereof I affix my signature in presence of two witnesses.

CHARLES G. MAYER, JR.
